United States Patent Office

Des. 188,890
Patented Sept. 27, 1960

188,890

PILLOW

William M. Emery, 44 Pittsford Way,
New Providence, N.J.

Filed June 17, 1959, Ser. No. 56,392

Term of patent 14 years

(Cl. D3—9)

FIG. 1

Figure 1 is a plan view of a pillow showing my new design; and Figure 2 is an edge view looking from the top of Figure 1.

The face not shown is substantially the same as the face shown in Fig. 1 with the ornamentation omitted.

I claim:

The ornamental design for a pillow, as shown and described.
